The invention relates to a new and original design for a wagon-stake; and it consists of a stake of the configuration shown in the accompanying drawings, in which—

5 Figure 1 is a perspective view of the stake, and Fig. 2 is a side view taken from the side opposite to that shown in Fig. 1.

1 denotes the tapering upright, rectangular in cross-section and having at its lower end a base 2, one end of which is curved and the other end of which is straight, and from the side edges of which project downwardly par-

allel flanges 3, the ends of which are vertical and the lower edges of which are scalloped, divergent rods 4 extending from one edge of 25 the stake to the base thereof, pyramidal lugs 5 projecting from the base on opposite sides of the upright and at the point of union of the upright with said base, the laterally-projecting lugs 6 extending from the edge of the stake at 30 a point midway its ends and having a flat upper surface and a rounded side and tapering ends which lie against the sides of the stake, and the arch 7.
